UNITED STATES PATENT OFFICE.

JEFFREY C. HORNEY, OF DALLAS, TEXAS, ASSIGNOR TO JACK B. CARTER, TRUSTEE,
OF DALLAS, TEXAS.

TRAFFIC SIGNAL.

1,413,915.

Specification of Letters Patent. Patented Apr. 25, 1922.

Application filed November 25, 1921. Serial No. 517,468.

To all whom it may concern:

Be it known that I, JEFFREY C. HORNEY, a citizen of the United States, residing at Dallas, in the county of Dallas and State of Texas, have invented certain new and useful Improvements in Traffic Signals, of which the following is a specification.

This invention relates to new and useful improvements in traffic signals.

10 The object of the invention is to provide a signal apparatus having a continuously moving target. Another object is to provide mechanism of simple construction for operating the target, said mechanism being driven by an electric motor.

15 A particular feature of the invention resides in means for keeping the operating mechanism well lubricated. Another feature resides in a resilient member connecting the motor with the mechanism.

20 A construction designed to carry out the invention will be hereinafter described together with other features of the invention.

25 The invention will be more readily understood from a reading of the following specification and by reference to the accompanying drawings, in which an example of the invention is shown and wherein:

30 Fig. 1 is an enlarged vertical sectional view of the operating box, showing the electric motor and operating mechanism therein,

Fig. 2 is an elevation of a signal apparatus constructed in accordance with my invention, and

35 Fig. 3 is an enlarged detail of the gears of the operating mechanism.

In the drawings the numeral 10 designates an upright post or support. Mounted on top of the post is an operating box 11, which

40 has a slot 12 in the top adjacent one end. A rock shaft 13 is mounted transversely and centrally of the slot and supported in bearing brackets 14. An upright arm 15 is mounted on the shaft, so that its upper or

45 outer end extends through the slot 12, while its lower portion depends from the shaft into the operating box. The upper end of the arm carries a target 16 which may be of any suitable design and is displayed clearly

50 above the box.

Located in the opposite end of the operating box is an operating mechanism 17 which is driven by an electric motor 18 mounted on a suitable support 19. The mechanism in-

cludes a worm gear 20 fastened on a transverse shaft 21 which has its bearings in upright supports 22 located on each side of a housing 23 covering the gears. A worm screw 24 is disposed longitudinally and above the gear 20 so as to mesh therewith. Suitable bearings 25 are provided in the housing for the shaft of the said screw, the driving end 26 of which extends through the housing and is connected to the shaft of the motor by means of a resilient connecting member 27. The said member as shown in the drawings is in the form of a spring, however, any other connecting member of a resilient character may be used, if desired. The resilient member is of particular advantage as it will be readily seen that the said member compensates for any distortion or unalignment of shafts, thereby preventing the motor from heating because of lateral displacement of the armature thereof.

70 The lower portion of the housing 23 comprises a tank for containing lubricating oil in which the gear 20 revolves. It is pointed out that the gear and screw are thereby kept well lubricated, and it will be readily seen that sufficient oil is splashed and thrown from the revolving gear to lubricate the bearings thereof as well as the bearings of the screw.

75 Mounted on the outer end of the shaft 21 and secured by means of a set screw 28 or the like, is a bar 29 to one end of which is pivoted a pitman 30, the other end of the pitman being pivoted to the lower end of the arm 15. It will be readily seen that as the bar is rotated, the pitman is reciprocated, whereby the arm 15 carrying the signal target is swung.

80 On each side of the operating box and mounted on the post or support 10 is a signal board 31 on which the usual crossing warning may be printed. A display panel 32 may be mounted on each side of the post below the signal board, on which suitable matter may be displayed.

85 It is pointed out that an apparatus constructed in accordance with my invention provides simple and efficient means for operating a continuously moving signal target. The construction comprises a minimum 90 number of parts, and the operating mechanism is self lubricating.

100 Various changes in the size and shape of

the different parts as well as modifications may be made, without departing from the spirit of the invention.

What I claim, is:

- 5 1. In a traffic signal, the combination of an upright support, an operating box mounted on the top of the support, a continuously swinging traffic signalling target carried by the box, an electric motor mounted in the 10 box, a worm gear mechanism mounted in the box, a resilient member connecting the motor with the gear mechanism, a rotating bar carried by the said mechanism, a pitman connecting the target with the said bar, and 15 a housing enclosing the said mechanism.
2. In a traffic signal, the combination of an operating box having a slot in its top, a target arm pivotally mounted and extending through said slot, a target on said arm above 20 the top of the box, an electric motor mounted in said box, a worm connected directly with the motor shaft, a worm wheel meshing with the worm, a bar mounted intermediate its ends on the shaft of the worm wheel, and a

pitman having one end pivotally connected 25 with one end of the bar and the other end pivotally connected with the lower end of the target arm.

3. In a traffic signal, the combination of an operating box having a slot in its top, a target arm pivotally mounted and extending through said slot, a target on said arm above the top of the box, an electric motor mounted in said box, a gear housing mounted in the box, a worm mounted in the upper portion of the housing, a shaft extending transversely from the housing, a worm wheel in the housing and meshing with the worm, the worm having a flexible connection direct with the motor shaft, the housing containing 40 a bath of oil in which the worm wheel is immersed, a rotating member mounted on the transverse shaft exteriorly of the housing, and a pitman having one end pivoted to the rotating member and its opposite end pivoted to the lower end of the target arm. 45

In testimony whereof I affix my signature.

JEFFREY C. HORNEY.
